UNITED STATES PATENT OFFICE.

ETHAN S. COLEMAN, OF TOLEDO, OHIO.

FILM-DEVELOPING RACK.

Application filed July 7, 1924. Serial No. 724,677.

To all whom it may concern:

Be it known that I, ETHAN S. COLEMAN, a citizen of the United States, residing at Toledo, in the county of Lucas and State of Ohio, have invented certain new and useful Improvements in Film-Developing Racks; and I do declare the following to be a full, clear, and exact description of the invention, such as will enable others skilled in the art 10 to which it appertains to make and use the same.

When developing a plurality of photographic films, it is customary to hang such films upon a rack and lower the rack and 15 films to immerse the latter in the developing solution. A great deal of difficulty is often encountered however, in preventing contact of the films with each other and consequent scratching thereof. This difficulty 20 is particularly prevalent when the immersing frame is moved upwardly and downwardly to break the minute air bubbles which commonly form on the surfaces of the films. It is the principal object of my 25 invention however to provide an improved type of developing rack, in which novel means are provided for supporting the films and holding them in spaced relation, so that they cannot come in contact with 30 each other, even though they may transversely curl in the usual manner.

Another object of the invention is to provide a developing rack of simple and inexpensive construction, one which may be 35 easily and rapidly operated, and a device which will be generally efficient and desirable.

With the foregoing and minor objects in 40 view, the invention resides in the novel subject matter hereinafter described and claimed, the description being supplemented by the accompanying drawings.

Figure 1 is a side elevation of one form 45 of the rack showing a number of films supported thereby.

Figure 2 is a view similar to Fig. 1 but illustrating the manner in which the film spreaders may be held in elevated positions to permit the films to be easily applied to or 50 removed from the suspending devices.

Figure 3 is a vertical sectional view as indicated by line 3—3 of Fig. 1.

Figure 4 is a horizontal sectional view on line 4—4 of Fig. 1, showing more particularly the construction of one of the film 55 spreaders.

Figure 5 is a side elevation showing a modified form of construction, with one of the vertical rods shown in Fig. 8 omitted in order that one of the films may be clearly 60 shown suspended from the hanger.

Fig. 6 is a plan view of the hanger shown in Fig. 5, with the suspending rod shown in section.

Figure 7 is a horizontal sectional view on line 7—7 of Fig. 5.

Figure 8 is a fragmentary perspective view of a portion of the frame structure shown in Fig. 5.

In describing my invention, I will first 70 refer to the form of construction shown in Figs. 1 to 4 and while this construction will be rather specifically described, it is to be understood at the outset, that within the scope of the invention as claimed, numerous 75 modifications may be made.

The numeral 1 designates a horizontal supporting bar which may be suspended in any of the usual ways. A pair of inverted L-shaped arms 2 are secured to this bar and 80 project rearwardly and downwardly therefrom, in inwardly spaced relation with its ends, the lower ends of said arms carrying a horizontal bar 3 to which a plurality of vertical hook shanks 4 are secured, said 85 shanks having hooks 5 at their lower ends, which are preferably disposed horizontally for engagement with any desired film clips 6 for holding the films 7 to be developed. A horizontal guard rod 8 is adapted to extend 90 across the free ends of all of the hooks 5, one end of this rod being shown loosely pivoted at 9 to a vertical rod 10 which depends from the supporting bar 1, while the other end of the rod 8 is detachably engaged 95 with a hook 11 on a second rod 12 projecting downwardly from said bar.

At suitable points, spaced inwardly from the ends of the bar 1, are transverse straps 13 which are secured to said bar and project 100 oppositely therefrom. These straps support a plurality of vertical rods 14 whose lower ends are suitably connected by a lower end frame 15. Slidable along the rods 14, I have shown upper and lower film spreaders 16 and 17, each of which may well be of the construction detailed in Fig. 4. In this 105 view, the spreader 17 is shown as consisting of a frame formed of parallel side bars or rods 18, and end bars 19, transverse film spacing members 20 being extended between said side bars. In the construction shown,

the spacing members 20 are formed by reaches of a flexible line, such as a silk or cotton fishing line, and to hold these spreading members or reaches in properly spaced relation, the line is coiled around the side bars 18 between the reaches, as indicated at 21. It will be seen that these reaches and the side bars constitute separate film guides for the films 7, and that such guides will 10 not permit excessive transverse curling of the films. This is indicated by dotted lines in Fig. 4, from which view, it will be seen that when any film curls toward its gelatine-coated face, the edges of the film will abut 15 one of the spacing members 20 and the center of the film will abut the adjacent spacing member, at the reverse side of the film, so that these spacing members can at no time come in contact with the gelatine coating of the film to in any manner injure the latter. It is of course understood that when 20 applying the films to the rack, they are all faced in the same direction, so that when they curl in the usual manner, all parts thereof will be effectively held in spaced relation. Preferably, additional clips 22 are applied to the lower extremities of the films and they exert sufficient weight thereon to hold said films taut, yet they have no excessive stretching effect on the films, such as 25 certain weights which are commonly used.

The two spreaders 16 and 17 are provided with appropriate guides 23 which are slideable along the rods 14, so as to permit vertical movement of said spreaders. When the spreader 17 is lowered, its descent is limited by the base frame 15, and any desired means may be employed to hold the spreader 16 at a position between the spreader 17 and the hooks 5. Merely, for 35 illustrative purposes, removable pins 24 have been shown, passing through openings 25 in the rods 14, for this purpose. When the spreaders 16 and 17 are raised to the maximum, they are above the hooks 5 and the film guides, defined by the side bars 18 and the spacing members 20, then occupy 40 positions around the hook shanks 4. Thus, the hooks 5 are readily accessible to permit 45 the engagement of the films therewith or removal therefrom. When removing the films from the hooks, the rod 8 will of course first be released and swung downwardly, as indicated in Fig. 2. Then, too, 50 it will be understood that after the films have been engaged with the hooks prior to developing, the bar 8 is swung upwardly and engaged with the hook 11.

Any desired means may be employed to 60 hold the spreaders 16 and 17 in the raised position of Fig. 2, but for illustrative purposes, I have shown a hook 26 pivoted to the bar 1 and engageable with a transverse rod 27 with which the spreader 17 is provided.

After applying the clips 6 to the hooks 5 and labeling the films in the usual manner, the spreaders 16 and 17 are lowered to operative positions, and the rod 8 is then secured in operative position. Then, the entire rack and the films carried thereby may be immersed in the developing tank and the rack may be shaken as much as desired to break the air bubbles which commonly form on the films, without danger of these films 70 coming in contact with and injuring each other. The rack is of such a size that a plurality of duplicate racks may be simultaneously inserted into a single developing tank, or the like, enabling the photographer to simultaneously develop an unusual number of 75 films. When the films have been immersed for the proper time the rack is of course removed, the rod 8 is released, the spreaders 80 16 and 17 are moved upwardly to the position of Fig. 2 and the films are detached 85 from the hooks 5 and hung upon any desired drying rack.

In the construction shown in Figs. 5 to 8, a circular design is shown, for use in connection with certain forms of circular developing tanks. 1^a designates a suitable support from which a hanger 2^a extends downwardly to support a ring 3^a to which the shanks of hooks 5^a are secured, said hooks being radially disposed, as shown clearly in Fig. 6. Rods 14^a extend downwardly from the support 1^a and may well be connected at their lower ends by a ring 15^a, and spreaders 16^a and 17^a, are movable along the rods and may be held in raised position by hooks 26^a.

Each of the spreaders 16^a and 17^a preferably comprises inner and outer rings 18^a and 18^b connected at intervals by radial rods 27^a and radial film spacing members 20^a. These spacing members like the members 20, are preferably formed from flexible lines, and the lines are coiled around the rings between the members 20^a, as indicated at 21^a.

The use of the construction just described will be apparent and it will be equally as efficient as the form of construction first described. Both forms of the invention are very desirable in every way and these forms may be followed if desired in the manufacture of the device, but within the scope of the invention as claimed, numerous changes may be made, as above stated, and it is obvious that I am not restricted to the number of hooks, spreaders and other parts, which may be used. Two spreaders are usually sufficient, but any desired number may be employed.

I claim: —

1. A film developing rack comprising a support having a plurality of film suspending devices, a film spreader movable to a position above the film-engaging portions of the suspending devices to permit engage- 120

ment of the films with said devices or removal therefrom, and means for holding said spreader in a lowered operative position to hold the films in spaced relation.

5 2. A film developing rack comprising a support having a plurality of film suspending devices, a film spreader movable to a position above the film-engaging portions of the suspending devices to permit engagement

10 of the films with said devices or removal therefrom, and a plurality of rods depending from said support for guiding said spreader to and holding it in a lowered operative position to hold the films in spaced

15 relation, said spreader having guides movable along said rods.

3. A film developing rack comprising a support, a plurality of downwardly projecting hook shanks carried by said support

20 and having hooks at their lower ends for suspending films, a vertically movable film spreading frame having film guides movable to positions above said hook shanks when the frame is raised, permitting easy engagement of films with the hooks or removal therefrom, and means for holding said frame in a lowered operative position to hold the films in spaced relation.

25 4. A structure as specified in claim 3; together with a guard rod adapted to extend across the free ends of all of said hooks

to retain the films in engagement therewith, and means for releasably holding said guard rod in operative position.

5. A structure as specified in claim 1; 35 said film spreader comprising a frame having horizontal side members to extend across the edges of the films, and transverse members extending horizontally between said side members in spaced relation to pass between the films.

6. A structure as specified in claim 1; 45 said film spreader comprising a frame having horizontal side members to extend across the edges of the films, and a flexible line 45 having horizontal reaches extending between said side members to pass between the films, said line being coiled around the side members between the aforesaid reaches to hold the latter in spaced relation.

7. A film developing rack comprising a plurality of film suspending devices, a plurality of film spreading frames for engagement with the films at different elevations, and means for holding said spreaders and 55 suspending devices in substantially rigid relation while immersing the films in a developing solution.

In testimony whereof I have hereunto affixed my signature.

ETHAN S. COLEMAN.
